UNITED STATES PATENT OFFICE.

ROBERT BJORKLUND, OF WORCESTER, MASSACHUSETTS.

CARBURETER.

1,161,374.

Specification of Letters Patent.

Patented Nov. 23, 1915.

Application filed February 23, 1915. Serial No. 9,875.

To all whom it may concern:

Be it known that I, ROBERT BJORKLUND, a subject of the King of Sweden, residing at Worcester, in the county of Worcester and 5 State of Massachusetts, have invented a new and useful Carbureter, of which the following is a specification.

This invention relates to a carbureter for an internal combustion engine and more 10 particularly to improved devices for controlling the proportions of the fuel and air mixture in such carbureter.

In the operation of an internal combustion engine, the supply of air must necessarily 15 vary with the speed of the engine, and the supply of fuel should also vary in some fixed relation to the supply of air. This relation, however, is not constant as the relative proportions of air and fuel for a given speed are determined in part by 20 temperature and weather conditions, as well as by the quality of the fuel, and by other variable factors.

It is the object of my invention to provide 25 improved devices for varying the supply of fuel proportionately with variations in the supply of air; and also to provide for changing the relative proportions of fuel and air to correspond to actual conditions of operation.

A further object of my invention is to improve the construction of carbureters of the class described and to increase their efficiency, while at the same time attaining simplicity of parts and cheapness of manufacture.

The features of my invention relate to certain devices, arrangements and combinations of parts which will be hereinafter described and more particularly pointed out in the appended claims, said features possessing advantages in simplicity of construction and ease of operation which will be apparent to those skilled in the art.

A preferred form of my invention is 45 shown in the drawings, in which—

Figure 1 is a vertical sectional view of a carbureter embodying my invention; Fig. 2 is a transverse sectional view taken along 50 the line 2—2 in Fig. 1. Fig. 3 is a similar view taken along the line 3—3 in Fig. 1; Fig. 4 is a side elevation of the inner frame of the carbureter, and Fig. 5 is a detail view to be described.

As shown in the drawings, my improved carbureter comprises a casing 10 having a 55 frame 11 extending upwardly in an inclined

position and secured within the casing. The fuel inlet is indicated at 12, the air inlet at 13 and the outlet to the engine cylinder at 14. In its lower portion the frame 11 is provided with an air inlet passage 15, said passage being open at its upper end as indicated at 15^a for the admission of air from the air inlet 13 and terminating in two 60 branch passages 15^b opening into the mixture chamber 15. An adjustable nozzle 17 is mounted to slide in a recess in the lower portion of the frame 11, said nozzle projecting into the air inlet passage 15 and being 65 normally forced outward into said recess by a coil spring 18. A nozzle-adjusting lever 19 is pivoted at 20 to the frame 11 and is forked at its lower end to engage a shoulder on the nozzle 17. At its upper end the 70 lever is provided with a cam-shaped portion 21 positioned for engagement by a stud 22 projecting through a slot 23 in the wall of the casing 10 and carried by a ring 24 angularly movable upon the outer surface of said 75 casing. With this construction it will be evident that angular movement of the adjusting ring 24 will be effective through the stud 22 to move the lever 19, thus forcing the nozzle 17 rearwardly in its recess. Said 80 recess at its lower end communicates through a passage 25 with a float chamber 26, the flow of fuel to said chamber being controlled by a needle valve 27 which is opened by a float 28 when the fuel level in the chamber 90 falls below a given point. The float 28 is mounted upon an arm 29 which is movable about a pivot 30 positioned eccentrically upon a screw stud 31. The stud 31 is mounted in an extension 32 of the casing 10 and 95 is provided with a knurled head 33 by which it can be adjusted. Angular adjustment of the stud 31 will change the normal fuel level in the chamber 26. The raising of the pivot 30 will permit the needle valve 27 to close 100 when the fuel in the chamber 26 has reached a comparatively low level, whereas lowering of the pivot 30 will necessitate the raising of the float to a correspondingly higher position before the valve is free to close. This 105 adjustment of the pivot will be most commonly utilized for priming the carbureter when it is necessary to start a cold engine. The head 33 may be provided with stop pins 34 adapted to coöperate with an index finger 110 35 to indicate the position of the pivot 30.

In its upper central portion the frame 11 is cut away as indicated in dotted lines at 11^a (Fig. 4) to provide an auxiliary air in-

let, said inlet being normally closed by a flat flexible valve member 36 having its lower end secured to the frame 11 in any convenient manner. As shown in the drawings, the member 36 is secured to the frame by a plate 37 and screws 37^a passing through said plate, into the frame and thereby clamping the valve member thereto. Near its lower end the member 36 carries a cap or 10 plug 38 which acts as a closure for the nozzle 17. Adjustment of the nozzle 17 relative to the closure 38, as previously described, provides a fixed initial opening of the nozzle through which a definite supply 15 of fuel is admitted to the mixing chamber, said fuel being carried into the chamber by the air flowing past said nozzle through the inlet passage 15.

The passage 15 is designed to supply the 20 full amount of air which will be required by the engine when running idle and the nozzle 17 should be adjusted by means of the adjusting ring 24 to permit the passage 25 of the suitable amount of fuel for mixture with this amount of air. As the speed of the engine increases an additional amount of air will be required and this air is admitted through the auxiliary air inlet 11^a, the suction of the engine causing the flexible 30 valve member 36 to be forced backward toward the dotted line position indicated in Fig. 1. As the closure 38 is carried by the valve member 36, the closure will be simultaneously moved away from the nozzle 17, thus admitting an additional amount of 35 gasoline corresponding proportionately to the increased supply of air. It will be seen that I have thus provided convenient and very simple mechanism for varying the fuel 40 supply proportionately to the air supplied to the mixing chamber.

It has been found, as previously explained, that it is necessary to vary the proportions of air and fuel in accordance with 45 the conditions under which the engine is operating and for this purpose I have provided means for varying the proportional relation between the movements of the valve member 36 and the nozzle closure 38. This 50 means comprises a coil spring 40 engaging the valve member 36 at a point above but adjacent the closure 38, and a lever 41 pivoted at 42 to the frame 11 and effective to regulate the pressure of the spring 40. For 55 the purposes of such regulation the lever 41 is provided with a cam-shaped head 41^a positioned for engagement by a stud 42 carried by a ring 43 and extending through a slot 44 near the upper end of the casing 10. The 60 lever 41 may be adjusted by turning the ring 43 in a manner substantially similar to the adjustment of the lever 19 and by such adjustment the tension of the spring 40 may be increased or diminished.

As the tension of the spring 40 is increased the movement of the closure 38 will be decreased relatively to the movement of the valve member 36, thus decreasing the proportion of fuel admitted to the mixing chamber with a given amount of air. I 65 have thus provided in an exceedingly simple manner for the adjustment of the fuel supply in different proportionate relations to the air supply. It should be further noted that the only moving part of my device is 70 the flexible valve member 36 and that the construction of this member avoids the necessity for any bearings or sliding or 75 rotating parts.

Having thus described my invention it 80 will be evident that changes and modifications can be made therein by those skilled in the art without departing from the spirit thereof as set forth in the claims and I do not wish to be otherwise limited to the details herein disclosed, but

What I claim is:—

1. A carbureter having, in combination, a casing, a frame therein, a mixing chamber having an air inlet thereto, said inlet being 90 constantly open and of fixed area, a nozzle opening into said inlet, means for adjusting said nozzle to admit a definite initial supply of gasoline to the mixing chamber, an auxiliary air inlet to said chamber normally 95 closed by a movable valve member, means whereby the movement of said valve member will vary the amount of gasoline admitted to the mixing chamber, and manually operable means to vary the effect of 100 said movable valve upon the amount of gasoline admitted to the mixing chamber.

2. A carbureter having, in combination, a casing, a frame therein, a mixing chamber having an air inlet thereto, a nozzle opening into said inlet, a closure for said nozzle, means for adjusting said nozzle relatively to said closure to provide for the admission of a definite initial supply of gasoline, an auxiliary air inlet to said mixing chamber normally closed by a movable valve member, said valve member and said nozzle closure being so connected that movement of 105 said member will cause proportional movements of said closure relatively to said nozzle, and means to vary the relative proportions of said movements.

3. A carbureter having, in combination, a casing, a frame therein, a mixing chamber having an air inlet thereto, a nozzle opening into said inlet, a closure for said nozzle, means for adjusting said nozzle relatively to said closure to provide for the admission of a definite initial supply of gasoline, an auxiliary air inlet to said mixing chamber 110 normally closed by a flexible valve member fixedly supported at one end on said frame and having the other end free, said closure

being carried by said member and movable therewith to increase or decrease the nozzle opening.

4. A carbureter having, in combination, a casing, a frame therein, a mixing chamber having an air inlet thereto, a nozzle opening into said inlet, a closure for said nozzle, means for adjusting said nozzle relatively to said closure to provide for the ad-

10 mission of a definite initial supply of gasolene, an auxiliary air inlet to said mixing chamber normally closed by a flexible valve member fixedly supported at one end on said frame and having the other end free, said 15 closure being carried by said member and movable therewith to increase or decrease the nozzle opening, and means to vary the proportional movements of said closure relatively to the movements of the free end of 20 said member.

5. A carbureter having, in combination, a casing, a frame therein, a mixing chamber having an air inlet thereto, a nozzle opening into said inlet, a closure for said nozzle, 25 means for adjusting said nozzle relatively to said closure to provide for the admission of a definite initial supply of gasolene, and an auxiliary air inlet to said mixing chamber normally closed by a movable valve member, 30 said member comprising a flat spring plate fixed at one end to said frame and having the nozzle closure mounted thereon, movement of the free end of said plate causing a corresponding but proportionately reduced 35 movement of said closure.

6. A carbureter having, in combination, a casing, a frame therein, a mixing chamber having an air inlet thereto, a nozzle opening into said inlet, a closure for said nozzle, 40 means for adjusting said nozzle relatively to said closure to provide for the admission of a definite initial supply of gasolene, an auxiliary air inlet to said mixing chamber normally closed by a movable valve member, 45 said member comprising a flat spring plate fixed at one end to said frame and having the nozzle closure mounted thereon, movement of the free end of said plate causing a corresponding but proportionately reduced 50 movement of said closure, and means to vary the relative proportions of the movements of said plate and closure.

7. A carbureter having, in combination, a casing, a frame therein, a mixing chamber 55 having an air inlet thereto, a nozzle opening into said inlet, a closure for said nozzle, means for adjusting said nozzle relatively to said closure to provide for the admission of a definite initial supply of gasolene, an auxiliary air inlet to said mixing chamber 60 normally closed by a movable valve member, said member comprising a flat spring plate fixed at one end to said frame and having

the nozzle closure mounted thereon, movement of the free end of said plate causing 65 a corresponding but proportionately reduced movement of said closure, a spring engaging said plate adjacent said closure, and means to vary the pressure of said spring on said plate, thereby varying the relative 70 proportional movements of said plate and closure.

8. A carbureter having, in combination, a casing, a frame therein, a mixing chamber having an air inlet thereto formed in said 75 frame, a nozzle opening into said inlet, a closure for said nozzle, means for adjusting said nozzle relatively to said closure to provide for the admission of a definite initial supply of gasolene, an auxiliary air inlet to 80 said mixing chamber normally closed by a movable valve member, said member comprising a flat spring plate fixed at one end to said frame and having the nozzle closure mounted thereon, movement of the free end 85 of said plate causing a corresponding but proportionately reduced movement of said closure, a spring engaging said plate between said closure and the free end of said plate, a lever pivoted to said frame and engaging one end of said spring, a ring supported by and angularly movable upon said casing, and connections between said ring and said lever whereby angular movement of said ring is effective to vary the pressure 90 of said spring.

9. A carbureter having, in combination, a casing, a spring-pressed nozzle movably supported therein, a closure for said nozzle, an adjustable stop for positioning said nozzle, 100 a lever supporting said stop, and means comprising a ring angularly movable on the casing for moving said lever to adjust said nozzle relatively to said closure.

10. A carbureter having, in combination, a 105 casing, a nozzle movably mounted therein, a ring angularly adjustable on said casing and connections from said ring to said nozzle, whereby angular adjustment of said ring is effective to vary the position of said 110 nozzle, a movable closure for said nozzle and an auxiliary valve member supporting said closure, a second ring angularly adjustable on said casing, and connections from said second ring to said valve member whereby 115 angular adjustment of said second ring is effective to vary the proportional movements of said valve member and closure.

In testimony whereof I have hereunto set my hand, in the presence of two subscribing 120 witnesses.

ROBERT BJORKLUND.
